UNITED STATES PATENT OFFICE.

OSCAR MUSSINAN, OF NEW YORK, N. Y.

CUSHION PNEUMATIC HEEL.

1,231,777

Specification of Letters Patent.

Patented July 3, 1917.

Application filed August 22, 1916. Serial No. 116,288.

To all whom it may concern:

Be it known that I, OSCAR MUSSINAN, a citizen of the United States, and a resident of the borough of Manhattan, in the city 5 and State of New York, have invented certain new and useful Improvements in Cushion Pneumatic Heels, of which the following is a specification.

The invention relates to cushion heels, 10 and has for one of its principal objects to provide such a heel which shall be strong and durable, which shall be economical of material, and which shall take up a portion of the shock consequent upon the tread of 15 the wearer.

The invention consists in the novel construction, arrangement and combination of various elements and parts, as shown in the accompanying drawings and hereinafter 20 more particularly described.

In the said drawings, Figure 1 is a plan view of the upper face of my improved heel; Fig. 2 is a side view of the same; Fig. 3 is a section taken on the line 3—3 of Fig. 25 1; Fig. 4 is an end view; Fig. 5 is a plan view of the lower face; Fig. 6 is a section taken on the line 6—6 of Fig. 5; Fig. 7 is a section taken on the line 7—7 of Fig. 5; and Figs. 8 and 9 are plan views of the 30 lower and upper faces respectively, showing a modification which may be incorporated in my invention.

In carrying my invention into effect in the embodiment thereof which I have selected for illustration in Figs. 1 to 7 inclusive and description in this specification, I provide a heel formed of rubber or other flexible material provided with a peripheral tread portion 11, and an upper peripheral 40 portion 12 adapted to bear against the lower surface of the heel of a shoe or boot to which it may be attached. Suitable perforations 13 may be provided, through which may extend nails by means of which the 45 heel may be secured to the shoe or boot.

In the central portion of the lower face of the heel I provide an arched cavity 14. The shape of this cavity 14 may be best observed in Figs. 3 to 7 inclusive, where it will 50 be seen that it is open at the front of the heel, as shown at 15, but that on all other sides its walls curve downward and join the inner edge of the tread 11. At the center of the cavity 14 a secondary dome-shaped 55 cavity 16 extends toward the upper face of the heel. The tread 11 is broken at inter-

vals by arched cavities or grooves 17 which extend outward therethrough from the cavity 14 to the outer air.

On the upper face of the heel I provide 60 a cavity 18 within the portion 12. In the center of this cavity and opposite the depression 16 in the cavity 14 I provide a dome-shaped elevation 20 which may extend slightly above the level of the portion 65 12. The portion 12 is broken at intervals by means of depressions or grooves 19, connecting the cavity 18 with the outer air. It will be observed by an inspection of Fig. 2 that the depressions 19 are staggered with 70 relation to the depressions 17, and also that they are considerably smaller than the said depressions 17. I have designated the material between the upper and lower cavities 25.

In the modification shown in Figs. 8 and 75 9 I provide a heel having a tread portion 21, surrounding a cavity 22, analogous to the cavity 14, and provided with laterally extending cavities or grooves 23. The heel 80 may be provided with perforations 24, analogous to the perforations 13.

The upper face of the heel is provided with a peripheral portion 26, analogous to the portion 12, surrounding a depression 27, 85 which in turn surrounds a dome-shaped elevation 28. Extending laterally from the depression 27 are secondary depressions or grooves 29. This modification differs from that first described in that the outer ends 90 of the depressions or grooves 23 and 29 are closed by thin portions of material 30. These closures are for appearance, and do not in any way affect the operation of my invention. It is preferable, however, not to 95 hermetically close the chamber formed by the depression 27 when the heel is in place.

In use my cushion heel is attached in any suitable manner to the heel of a shoe or boot. When the foot is placed upon the ground 100 in walking, the weight of the body falls upon the tread. This tends to close the openings 19, (or 29), and the upward pressure is in turn transmitted to the chamber formed by the depression 18, (or 27), and 105 tends to compress this chamber against the pressure of the air therein and also against the resistance caused by the downward pressure of the heel of the shoe against the elevation 20, (or 28). My heel thus takes up the 110 shock of walking in three ways; first, by the compression of the material of the heel it-

self; second, by the compression of the air in the chamber 18; and third, by the bending of the portion 25. The lower portion of the heel is so formed as to produce a great amount of strength by the use of a small amount of material, and also to prevent or minimize possible slipping of the wearer's foot.

The advantages of my invention will thus 10 be obvious. I do not limit myself to the exact forms described, as it is evident that various other forms might be employed, without departing from the spirit and scope of my invention.

15 Having thus described my invention, what I claim as new and desire to secure by Letters Patent is as follows.

1. A heel provided with a peripheral tread portion, a depression in its lower face, 20 a depression extending laterally outward therefrom, and a depression in its upper face.

2. A heel provided with a peripheral tread portion, a depression in its lower face, 25 a depression of arched form extending laterally therefrom into said tread portion, and a depression in its upper face.

3. A heel provided with a peripheral tread portion, a depression in its lower face, 30 a depression extending laterally therefrom through said tread portion for a portion of its width only; and a depression in its upper face.

4. A heel provided with a peripheral 35 tread portion, a depression in its lower face, a secondary depression therein, and a depression in its upper face.

5. A heel provided with a peripheral tread portion, a depression in its lower face, 40 a depression in its upper face, and a lateral depression extending outwardly from said last named depression into said tread portion.

6. A heel provided with a peripheral tread portion, a depression in its lower face, 45 a depression in its upper face, and a lateral depression extending outwardly from said last named depression and through said tread portion for a portion of its width only.

7. A heel provided with a peripheral tread portion, a depression in its lower face, 50 a depression in its upper face, a groove extending laterally from one of said depressions, and a central elevation in said last 55 named depression.

8. A heel provided with a peripheral tread portion, a depression in its lower face, 60 a depression in its upper face, a groove extending laterally from one of said depressions, and a central elevation in said last named depression, said elevation extending above the level of the peripheral portion of the upper face of the heel.

9. A heel provided with a peripheral 65 tread portion, a depression in its lower face, secondary depressions extending laterally therefrom, a depression in its upper face, and secondary depressions extending laterally therefrom, said upper and lower depressions 70 being staggered with relation to each other.

10. A heel provided with a peripheral tread portion, a depression in its lower face, 75 a secondary depression therein, a depression in its upper face, and a central elevation in said last named depression.

11. A heel provided with a peripheral tread portion, a depression in its lower face, 80 a secondary depression therein, a depression in its upper face, and a central elevation in said last named depression, said elevation extending above the level of the peripheral portion of the upper face of the heel.

In witness whereof I have hereunto signed my name this 18th day of August, 1916.

OSCAR MUSSINAN.
